HEAT-TREATING FURNACE

Raymond J. Guba, Philadelphia, Pa., assignor to
Audubon Wire Cloth Corporation, a corporation
of New Jersey

Application July 28, 1943, Serial No. 496,683

13 Claims.

(Cl. 214—21)

The invention relates to a heat-treating furnace and is directly specifically to an improvement in the structure of the conveyor employed for transporting articles therethrough during the heat-treating operation.

In the construction of many types of furnaces used for annealing metal articles and for effecting other heat-treating operations, it is common practice to provide the furnace with a tunnel through which the articles under treatment are transported by means of a flexible, heat-resisting conveyor the active run of which is dragged over the tunnel floor or hearth. In order to withstand the high temperatures to which it is subjected, such a hearth is generally made of heat-resisting metal alloys or of refractory brick and is usually somewhat abrasive in character. As the wire from which the conveyor spirals are made must be of a character to withstand such temperatures as well as resist the abrasive action of the hearth, it is relatively expensive, thus making the cost of manufacture and maintenance of the conveyor an important item in the ultimate cost of the articles which are heat treated.

Inasmuch as the conveyor is usually arranged so that the loaded run thereof is dragged over the furnace hearth, the wire spirals of which it is constructed are subjected to a great amount of wear by reason of the high abrasive action of the castings or the refractory bricks used in lining the tunnel and thus forming the floor or hearth. This is particularly true under the present war program in view of the efforts of the manufacturers of ordnance and other war materials to reduce the time and cost of manufacture of such materials by using castings in a rough or unfinished state for the furnace hearth. The extreme wear on the conveyor spirals as they are dragged over a hearth made of rough or unfinished castings results in excessive damage to the spirals and premature failure of the conveyor.

It is therefore one of the principal objects of the present invention to provide such a furnace with a spiral wire conveyor which is so constructed that the spirals are not directly subjected to the abrading action of the hearth. Another object of the invention is the provision, in a woven wire conveyor, of means for resisting endwise contraction and expansion of the wire spirals. A further object of the invention is the provision, in a woven wire conveyor, of means which not only serves to prevent wear upon one surface thereof, but also to resist longitudinal contraction and expansion of the spirals of which the conveyor is formed and thereby prevent trans-

verse contraction of the conveyor itself when under tension. Other objects and advantages of the improvement will be apparent from the following description, taken with the accompanying drawing, wherein:

Fig. 1 is a vertical, longitudinal, sectional view through a portion of a heat-treating furnace in which the improvement is embodied;

Figs. 2, 3, 4 and 5 are bottom plan views illustrating the operating runs of different forms of conveyors with the present improvement incorporated therein; and

Fig. 6 is an enlarged detailed view of a portion of the structure shown in Fig. 1, and illustrating the manner in which the improved conveyor cooperates with the furnace hearth and with the rollers which support the operation run of the conveyor.

While the invention may be utilized with other types of heat-treating furnaces, it is illustrated in Figs. 1 and 6 of the drawings with a furnace 10 in which the articles 11 to be heat treated are transported through a tunnel 12 during the treating operation. Such a tunnel is usually lined with separate units 13 which may be metal castings or refractory brick. In any case the articles 11 are generally transported through the tunnel 12 by means of an endless conveyor 14 which is so arranged that the run which transports the articles is dragged over the tunnel floor or hearth 15 and is supported at its opposite ends by suitable means such as the rollers 16.

In order to eliminate the wear upon the lower surface of the conveyor 14 as its active run is dragged over the furnace hearth 15, means are provided on the surface of the conveyor for keeping the wire spirals of which it is constructed out of contact with the hearth, this means also serving to prevent longitudinal expansion and contraction of the spirals and thereby prevent transverse contraction of the conveyor when under tension. It is important that some means be utilized for preventing endwise contraction of the coils in view of the tension applied to the conveyor and the high temperatures to which it is subjected when the furnace is in use.

The improvement may be utilized with various forms of conveyor of the wire spiral type, some such forms being shown in Figs. 2, 3, 4 and 5 of the drawings. The conveyor illustrated in Fig. 2 is formed of wire spirals 17 of the same twist, interwoven in such a manner that the bights 18 along one edge of each spiral overlap within the bights 19 of the adjacent spiral to receive a connector rod 20 in a manner well understood in the

art. The free ends of the spirals 17 along the edges of the conveyor may be knuckled together and welded to the ends of the adjacent connector rods as shown at 21.

The means illustrated with this form of conveyor for maintaining the spirals 17 out of contact with the hearth 15 and for preventing longitudinal contraction and expansion of the spirals consists of a wear resisting rod 22 extending throughout the length of each spiral on the face which operates adjacent the hearth. As will be apparent from Fig. 2, alternate rods 22 have their opposite ends 23 bent inwardly into a position to be welded to the knuckled ends of the spirals and to the ends of the connector rods 20 by the welds 21. The remaining wear resisting rods 22 have their opposite ends 24 bent inwardly and welded or otherwise secured to the ends of connector rods 20 as shown. If desired, each of the wear rods 22 may be integral with its associated connector rod 20 so that a single weld, as indicated at 25, may be used to connect the wear rod to the connector rod. The wear resisting rods 22 are also welded to the end turns of the spirals as indicated at 26, and they may be welded to intermediate turns, as shown at 27, if desired.

As shown in Figs. 1 and 6 of the drawings, the wear resisting rods 22 maintain the conveyor belt 14 out of contact with the hearth 15 as the belt is dragged thereover in transporting the articles through the tunnel 12, and in this manner the wire spirals are protected against abrasive action. The rollers 16 or other means utilized for supporting the conveyor 14 at the ends of the tunnel may be provided with suitable grooves 28 for receiving the wear resisting rods 22. Such a construction may be utilized for providing a positive feed for the conveyor 14 where one of the rollers 16 is utilized as a driving means.

The conveyor illustrated in Fig. 3 is made up of a succession of spirals 30 of the same twist, each spiral being interwoven with adjacent spirals in such a manner that the bights 31 on one edge directly interengage the bights 32 of the adjacent spiral. The free ends of the spirals may be knuckled together as shown at 33. In this form of conveyor the wear resisting rods 34 are shown as employed with alternate spirals 30, and the opposite ends are welded to the end turns of the spirals as indicated at 35. The rods 34 may also be welded to intermediate turns of the spirals, as shown at 36, if desired.

In the form of conveyor illustrated in Fig. 4, the spirals 37 are of opposite twist and are so arranged that the bights 38 on the edge of each spiral overlap the bights 39 on the edge of an adjacent spiral to receive a sinuous connector rod 40 of a form well known in the art. Preferably the ends of the connector rods 40 are welded to the free ends of the spirals 37 as shown at 41. In this form of conveyor each spiral is provided with a wear resisting rod 42, and its opposite ends are welded to the end turns of the spiral as shown at 43. The wear resisting rod 42 may also be welded to intermediate turns as shown at 44.

The conveyor shown in Fig. 5 is constructed of alternating coil units 45 and 46, one unit being formed of coils of one twist and the other being formed of coils of the opposite twist. Coil units 45 and 46 are of a composite character and each comprises two spiral coils 47 and 48 threaded together in a manner well understood in the art, and having the free ends thereof welded together at the edges of the conveyor as

shown at 49 and 50. The bights 51 along the edges of each coil unit 45 are arranged to overlap the bights 52 along the edges of adjacent coil units 46, and a connector rod 53 extending through the overlapping portions of bights 51 and 52 serves to secure the units together in succession. Preferably, the two connector rods 53 in each coil unit 45 have their opposite ends welded to the end turns of the coils of that unit, as shown at 54. When constructed in this manner the connector rods are unitary with coil units 45, and each coil unit 46 is therefore free for hinging movement upon the two connector rods 53 which extend therethrough.

With this form of the improvement, wear resisting rods 55 are preferably provided for alternate coil units, that is, for units 45. The wear resisting rods 55 extend throughout the length of the coil unit on one face thereof and are welded to the end turns of the coil unit as shown at 56. The opposite ends of the wear resisting rods 55 are bent inwardly, as shown at 57, into a position whereby they may be secured to the ends of a connector rod 53 by the welds 58 which secure the ends of one of the connector rods 53 to the end turns of a spiral. It will be understood, however, that each wear rod 55 may be integral with its associated connector rod 53 so that a single weld may be used to connect the adjacent ends at one edge of the structure as described above in connection with Fig. 2. With this construction each wear resisting rod 55 thus becomes a structural part of the coil unit 45, that is, the unit to which the ends of the connector rods are secured.

As will be apparent from the above description, when the various forms of conveyor shown in Figs. 2, 3, 4 and 5 of the drawings are utilized with a heat-treating furnace such as shown in Figs. 1 and 6, the wear resisting rods 22, 34, 42 and 55 will serve to keep the conveyor spirals out of contact with the furnace hearth throughout the width of the conveyor. The abrasive action of the hearth upon the conveyor is therefore taken by the wear resisting rods, and the life of the spirals, or the conveyor proper, is measurably increased. It will also be apparent that the wear resisting rods also serve to resist contraction of the conveyor in a transverse direction, as the ends of these rods are secured to the end turns of the spirals which make up the conveyor.

While various forms of the improvement have been disclosed herein, together with certain arrangements of the parts utilized therewith, it will be understood that the invention is not limited to the precise structure and arrangement which has been shown and described. It will be understood further that the invention is intended to include all such forms of the improvement as come within the scope of the appended claims.

What is claimed is:

1. A heat-treating furnace comprising a hearth over which articles are transported, an endless conveyor made of helical coils of wire successively connected together to form a flexible structure and having one of its runs dragging over said hearth to transport articles through said furnace, and a wire cross rod secured to each of said coils and extending throughout the length of each coil on the face adjacent said hearth to protect said coils against abrasion.

2. A heat-treating furnace comprising a hearth over which articles are transported, an endless conveyor made of helical coils of wire successively connected together to form a flexible structure

and having one of its runs dragging over said hearth to transport articles through said furnace, and a wire cross rod extending throughout the length of each of said coils on the face adjacent said hearth to protect said coils against abrasion and having its opposite ends secured to the end turns of said coils to resist endwise contraction of said coils.

3. In a heat-treating furnace having a hearth over which articles are transported, an endless conveyor having one of its runs dragging over said hearth to transport articles through said furnace and comprising a plurality of helical coils of wire successively arranged in interlapping relation, a connecting rod extending through the overlapping portions of adjacent coils, and a cross rod extending throughout the length of each of said coils on the face adjacent said hearth to protect said coils against abrasion and having its opposite ends secured to the ends of a connecting rod and to the end turns of a coil to resist endwise contraction of said coils.

4. In a heat-treating furnace having a hearth over which articles are transported, an endless conveyor having one of its runs dragging over said hearth to transport articles through said furnace and comprising a plurality of helical coils of wire successively connected together to form a flexible structure, cross rods arranged at intervals on the face of said conveyor adjacent said hearth, each of said cross rods extending throughout the length of a coil to protect the coil against abrasion and having its opposite ends secured to the end turns of the coil to resist endwise contraction of the coils.

5. In a heat-treating furnace having a hearth over which articles are transported, an endless conveyor having one of its runs dragging over said hearth to transport articles through said furnace and comprising a plurality of helical coils of wire successively arranged in interlapping relation, a connecting rod extending through the overlapping portions of adjacent coils, cross rods arranged at intervals on said conveyor, each of said cross rods extending throughout the length of one of said coils on the face adjacent said hearth to protect the coil against abrasion and having its opposite ends secured to the ends of a connecting rod and to the end turns of a coil to resist endwise contraction of said coils.

6. A conveyor belt for transporting articles over the hearth of a heat-treating furnace or the like, comprising a plurality of helical coils of wire successively connected to form a flexible structure, and cross rods arranged at intervals on the surface of said belt operating adjacent said hearth to provide wear-resisting elements for maintaining said coils out of contact with said hearth, each of said cross rods extending throughout the length of one of said coils on the outer face thereof and having its opposite ends secured to the end turns of the coil to resist endwise contraction of the coil.

7. A conveyor belt for transporting articles over the hearth of a heat-treating furnace or the like, comprising a plurality of helical coils of wire successively connected to form a flexible structure, and a wire cross rod extending throughout the length of each coil on the face thereof operating adjacent said hearth to maintain said coils out of contact with said hearth and having the opposite ends thereof secured to the end turns of the coil to resist endwise contraction of said coils.

8. A conveyor belt for transporting articles

over the hearth of a heat-treating furnace or the like, comprising a plurality of helical coils of wire successively arranged with the turns of each interlapping the turns of adjacent coils,

5 a wire connector rod extending through the interlapping portions of successive coils to connect the coils together, and a wire cross rod extending throughout the length of each coil on the face thereof operating adjacent said hearth to maintain said coils out of contact with said hearth and having the opposite ends thereof secured to the end turns of the coil and to the ends of a connector rod to resist endwise contraction of said coils.

10 9. A conveyor belt for transporting articles over the hearth of a heat-treating furnace or the like, comprising a plurality of helical coils of wire having the turns of each interlapping the turns of adjacent coils to form a continuous fabric, a connector rod extending through each coil between the turns thereof and the interlapping turns of each adjacent coil, and a wear resisting rod extending from end to end of each of said coils on the face thereof operating adjacent said

25 hearth to maintain said coils out of contact with said hearth and having its opposite ends secured to the opposite ends of an adjacent connector rod and to the end turns of the associated coil.

10 10. A conveyor belt for transporting articles over the hearth of a heat-treating furnace, said belt being formed from a succession of flexibly connected units each comprising a helical coil of wire, a connector rod extending through the bights at one edge of the coil and having its

35 opposite ends secured to the opposite ends of the coil, and a wear-resisting rod on the face of the coil operating adjacent said hearth for maintaining the coil out of contact with said hearth and having its opposite ends secured to the end turns

40 of the coil.

11. A conveyor belt for transporting articles over the hearth of a heat-treating furnace, said belt being formed from a succession of flexibly connected units each comprising a helical coil of wire, a connector rod extending through the bights at one edge thereof and having its opposite ends secured to the opposite ends of the coil, and a wear resisting rod arranged centrally on the face of the coil operating adjacent said hearth

45 for maintaining the coil out of contact with said

50 hearth and having its opposite ends secured to the end turns of the coil and to the opposite ends of said connector rod.

12. In a woven wire conveyor for transporting articles over the hearth of a heat-treating furnace, a belt element comprising a flattened helical coil of wire, and a cross wire arranged centrally on one of the outer faces of the coil to maintain the coil out of contact with said hearth and protect the coil from wear and having its opposite ends secured to the end turns of the coil to resist endwise contraction of the coil.

13. In a woven wire conveyor for transporting articles over the hearth of a heat-treating furnace, a belt element comprising a flattened helical coil of wire, a connector rod extending through the bights of the turns along one edge of said coil, and a cross rod arranged lengthwise on one of the outer faces of said coil to maintain the coil out of contact with said hearth and protect said coil from wear and having its opposite ends secured to the opposite ends of said coil and to the opposite ends of said connector rod to resist endwise contraction of said coil.
